UNITED STATES PATENT OFFICE.

THURE E. DAHL, OF NEW YORK, N. Y., ASSIGNOR TO LIGHTOLIER COMPANY, OF NEW YORK, N. Y., A CORPORATION OF NEW YORK.

DESIGN FOR A SIDE PANEL FOR LANTERNS.

Application filed July 21, 1921. Serial No. 486,589. Term of patent 3½ years.

To all whom it may concern:

Be it known that I, THURE E. DAHL, a subject of the King of Sweden, and residing at New York, in the county of New York and State of New York, have invented a certain new, original, and ornamental Design for a Side Panel for Lanterns, of which the following is a specification, ref-

erence being had to the accompanying drawing, forming part thereof.

The figure is a perspective view of a side panel for lanterns, showing my new design.

I claim:

The ornamental design for a side panel for lanterns, as shown.

THURE E. DAHL.
